UNITED STATES PATENT OFFICE.

JOHN W. DARLEY, JR., OF BALTIMORE, MARYLAND.

LOOP-FORMER FOR SEWING-MACHINES.

1,134,946.

Specification of Letters Patent.

Patented Apr. 6, 1915.

Application filed April 2, 1910. Serial No. 553,027.

To all whom it may concern:

Be it known that I, JOHN W. DARLEY, Jr., a citizen of the United States, residing at Baltimore, in the State of Maryland, have 5 invented certain new and useful Improvements in Loop-Formers for Sewing-Machines; and I do hereby declare the following to be a full, clear, and exact description of the invention, such as will enable others 10 skilled in the art to which it appertains to make and use the same.

My invention relates to improvements in loop formers for sewing machines and is of general application to all kinds of sewing 15 machines.

It is well known that in the ordinary sewing machine as at present constructed, the loop in the needle thread is formed by the action of the resistance of the work upon 20 the thread while the needle is being drawn back. In sewing machines which operate at a very high speed, or which operate upon a very thin fabric affording small resistance to the passage of the thread, this resistance 25 is not always sufficient to produce the loop, the result being that stitches are skipped and the sewing is imperfect. Various attempts to remedy this have been made, such as by using paper or backing for the thin 30 fabric, in order to increase this resistance, but this is unsatisfactory, as the appearance of the goods is apt to be unsightly and it is troublesome to remove the paper or backing. By my invention, however, the loop 35 is positively and automatically formed by the parts of the machine itself, no matter whether the resistance due to the fabric is large or small.

With this object in view, my invention 40 consists in the construction and combinations of parts as hereinafter described and claimed.

In the accompanying drawings Figure 1 45 is a side elevation, showing a machine of a well known type equipped with my improvement, the sewing mechanism, driving mechanism, tension mechanism, and take-up mechanism being all of well known or standard types. Fig. 2 is a cross-section through the 50 end of the machine containing the shuttle,

and showing the needle in the position of rest. Fig. 3 is a cross-section thereof taken on the line 3-3 of Fig. 2. Fig. 4 is a top plan view thereof, the guard and supporting plate being shown in cross-section. Fig. 5 shows the loop former enlarged, with the gripper operating upon the needle thread. Fig. 6 is a perspective view, on a larger scale, showing the shuttle and related parts. Fig. 7 is an end view of the shuttle and related parts, showing the needle just after the loop has been formed. Fig. 8 is a view of the shuttle and related parts just at the end of the sewing and loop forming operation. Fig. 9 is a perspective view, on a larger scale, of part of the shuttle and loop forming devices, showing the parts just as the loop is beginning to be formed, and Fig. 10 is a top plan view of the loop former and related parts, on a larger scale, the needle 70 being shown in cross-section.

1 represents a sewing machine of any approved type, and the usual operating means for operating the shaft 2. The details of this machine are not shown, as they are old 75 and well known in the art. The shaft 2, however, has a vibratory motion of one-half a revolution in the machine shown, but my invention is applicable to any form of sewing machine. One end of the shaft 2 passes 80 through a perforation in the bottom plate 3 of the machine, which forms a bearing therefor. This bearing plate is hollowed away, as shown at 4, for the driving mechanism, and also is shown at 5, the end being 85 protected by a pivoted guard 6, normally held in position by the spring 7, all of these parts being of a well known construction.

8 represents a ring, adapted to be screwed 90 against the end of the plate 3, being secured therein by screws passing through the openings 9. This ring is provided with a recess 10, forming a race way for the shuttle. The shuttle is retained in position within the ring 8 by another ring 11, which is 95 adapted to be screwed against the face of the ring 8 by screws entering the holes 12.

On the end of the shaft 2 is screwed a circular enlargement 13, which is provided with an arm 14, which is expanded, forming 100

a fork having an upward projection 15 and a downward projection 16, as shown in Fig. 8. These forks are adapted to engage the shuttle at times, at points 17 or 17^a, producing a vibratory motion of the shuttle, in the usual way in this type of machine. Centrally of the shuttle is fixed a pin 19, having a recess 20. On this pin, the bobbin case 21 is adapted to fit, and the pin is provided with a cut away portion 20, in which any spring-operated means may be adapted to engage.

The top of the ring 8 is cut away, as shown in Fig. 6, and against one edge of the 15 cut away portion is fitted a screw 22, which is provided with a shoulder and confines the plate 23 on the top of the ring. Pivotally mounted upon the shouldered portion of the screw 22, is the loop former 24, which consists of a horizontally extending arm provided with a downwardly curved portion 25. It is also provided with a cut away portion 26, provided with teeth and slightly larger than the diameter of the needle, so that it 20 may embrace the rear side of the needle momentarily at the proper time. Attached to the loop former near its center and opposite the toothed portion, is a projection 27, which inclines downwardly and inwardly, as 25 best shown in Fig. 9, and is beveled off as shown at 28.

The purpose of the loop former is to momentarily engage the needle threads on the side of the needle on which the shuttle takes 30 the loop. By having the loop former curved downwardly as shown at 25, two results are obtained. A firm bearing for the loose end of the loop former is provided, and the loop former is prevented from moving too far 35 in the direction in which it approaches the needle, should the machine be run without a needle. The end 25 is curved downwardly, so that at times it may engage the incline 40 29 on one end of the ring 8, and a stop 30 45 is provided on said end, so as to limit the movement of the loop former in one direction. The screw 22 is provided with a cylindrical washer, and the perforated end of the loop former is held in place between the 50 top of said washer and the head of the screw 22. Around this washer is coiled a spring 31, one end being secured to the plate 23, and the other bearing against the loop former, said spring tending always to bring 55 the loop former toward the needle. The shuttle is of any ordinary or well known type.

The operation is as follows: As the needle reaches practically the lowest limit of its 60 motion and begins to rise, as shown in Fig. 6, the hook 32 of the shuttle has just disengaged the projection 27, allowing the spring 31 to move the loop former toward the needle, whereupon said loop former engages

the thread as the needle commences to rise, 65 as shown in Figs. 5, 9, and 10, which show the needle after it has moved back a short distance from the position shown in Fig. 6. As shown in Fig. 9, the hook 32 is just upon the point of entering the loop, and as it enters the loop it strikes the projection 27 of the loop former, throwing the latter aside, until as shown in Fig. 7, the hook 32 has entirely engaged the loop and the loop former is pushed back. The sewing operation 70 then continues, the shuttle being moved around into the position shown in Fig. 8, at which time the take-up pulls the loop upward to pull the same tight upon the bottom of the fabric. Just before the parts reach 75 the position shown in Fig. 8, the shuttle is disengaged from the projection 27, but the arm 15 takes its place, preventing the loop former from striking the thread and leaving a space, as shown in Fig. 8, through 80 which the loop may be drawn tight, the parts being so constructed as to afford the proper clearance. It should be noted that the loop former is entirely kept out of operation and does not interfere in the slightest 85 with the action of the machine, except that it momentarily engages the thread when the loop is formed, as already described and as shown in Figs. 5, 9, and 10. It should also be noted that the loop former may be operated by any desired means.

While in the drawings my invention has been shown in connection with a lock stitch, it is equally applicable to chain stitch machines, to machines having double needles, 100 and in fact to every sewing machine in which a loop is formed in the needle thread.

I claim:—

1. The combination of a needle adapted to carry a thread, a coöperating stitch forming mechanism, a toothed member adapted to press upon said thread on the side of the needle next to said coöperating stitch forming mechanism to form a loop therein, means for operating said needle and coöperating 105 stitch forming mechanism.

2. In a sewing machine, the combination with a needle adapted to carry a thread and means for reciprocating said needle, with a loop former adapted, during the withdrawal 115 of the needle, to hold said thread, thereby forming a loop, a shuttle, and shuttle-operating means, said parts being so constructed that the loop former is held out of engagement with said needle, except momentarily, 120 at one time by the shuttle, and at another time by the shuttle operating means, substantially as described.

3. In a sewing machine, the combination of a needle adapted to carry a thread, means 125 for reciprocating said needle, a spring-controlled loop former, adapted to press the thread against the needle during the with-

drawal of the latter, thereby forming a loop, a shuttle, and shuttle operating means, said loop former being provided with a projection extending into the path of the shuttle and into the path of the shuttle operating means, whereby the loop former is held out of connection with said thread except momentarily, first by the shuttle and then by

the shuttle operating means, substantially as described.

In testimony whereof, I affix my signature, in presence of two witnesses.

JOHN W. DARLEY, JR.
